UNITED STATES PATENT OFFICE.

JOHN F. RYAN, OF HUNTINGTON, WEST VIRGINIA.

CHANGEABLE EXHIBITOR.

Application filed September 21, 1923. Serial No. 664,073.

To all whom it may concern:

Be it known that I, JOHN F. RYAN, a citizen of the United States, residing at Huntington, in the county of Cabell and State of West Virginia, have invented new and useful Improvements in Changeable Exhibitors, of which the following is a specification.

This invention has reference to an advertising device.

An object is the production of a device of this character in which cards containing advertising matter will be successively presented to view.

A further object is to produce an advertising device that includes a housing having its faces provided with diagonally disposed sight openings and divided by cleats on the sides and spaced from the faces thereof into an upper and a lower compartment, each of which having cards to be displayed therein and said cards being arranged in suitable frames, the cards in the lower compartment fully filling the same, the cards in the upper compartment being one less in number than those in the lower compartment whereby the diagonally opposed end cards in the respective compartments will be shifted from one to the other compartment by the turning of the housing, the means for turning the housing being such as to sustain said housing against movement for a considerable period of time when the cards therein are in display position.

To the attainment of the foregoing and other objects which will present themselves as the nature of the invention is better understood, reference is to be had to the drawings which accompany and which form part of this application.

In the drawings:—

Figure 1 is a front elevation of the improvement.

Figure 2 is an end elevation thereof with parts broken away.

Figure 3 is an approximately central vertical longitudinal sectional view through the housing.

Figure 4 is a fragmentary plan view of the base of the improvement to illustrate the drive means which rotates the housing.

Figure 5 is a fragmentary elevation of one of the hollow standards to illustrate the stop means which momentarily halts the turning of the housing.

Figure 6 is a perspective view of one of the card carrying frames.

Figure 7 is a sectional view approximately on the line 7—7 of Figure 4.

Figure 8 is a fragmentary sectional view approximately on the line 8—8 of Figure 7.

As disclosed by the drawings I make use of a substantially rectangular hollow base 1. The base has hinged to the open top thereof a flanged cover 2, suitable means 3 being employed for holding the cover in closed position. On the top of the cover 2 there is centrally arranged a hollow longitudinally extending projection 4 from whose ends there arise hollow standards 5 and 6 respectively. The outer faces of the standards are open, but are closed by removable plates 7 respectively.

In the base 1 there is secured a suitable casing 8 on which is mounted an electrically driven motor 9. The motor has its shaft, at one of its ends, provided with a governor, which in the showing of the drawings, is in the nature of a fan 10. The opposite end of the motor shaft has secured thereon a flexible shaft 11 connected by a coupling 12 to a shaft 13 which is journaled in bearings in a box-like housing 14. The shaft 13 has secured thereon a worm wheel 15 which meshes with a worm arranged therebelow and secured on a shaft 16 which has its ends journaled in bearings in the ends of the housing 14. On the said shaft 16 there is a worm wheel 17 in mesh with a worm gear 18 on a shaft 19 which is also journaled in suitable bearings in the housing and which projects through one end thereof.

Loosely journaled on the shaft 19, in a line with the center of the standard 6 there is a sprocket wheel 20. The wheel 20 has on one of its faces a pin 21 which is in the path of contact with a similar pin 22 secured on a sleeve 23 that is fixed on the shaft 19. On the outer end of the shaft 19 there is a fixed sleeve or collar 24 that has attached thereto one end of a coiled spring 25, the opposite end of the said spring being arranged at an angle and let into the sprocket wheel 20. By an arrangement as above set forth it will be noted that the speed imparted by the motor shaft to the shaft 19 is greatly reduced, and the arrangement of the spring 25 in connection with the sprocket wheel serves as a shock absorber for the sprocket wheel 20 and elements associated therewith when the card

holding housing (hereinafter to be described) is rotated and sustained in vertical positions.

Around the sprocket wheel 20 there is trained an endless chain 26 which is also trained around a similar sprocket wheel on a stub shaft 27 that is journaled in suitable bearings in the hollow standard 6. The last mentioned sprocket wheel 28 is freely journaled on the shaft 27, while fixed on the said shaft there is a wheel 29 having oppositely spaced projecting shoulders 30 and 31 respectively. On the chain 26 there are outstanding pins 32 in the path of contact with the said shoulders 30 or 31 and whereby the stub shaft 27 will be turned by such contact.

The stub shaft 27 is fixed centrally to one side of a frame-like structure which, for convenience, I will hereinafter refer to as a housing. The housing is broadly indicated by the numeral 33, and has on its side directly opposite that provided with the stub shaft 27, a second stub shaft 34. This stub shaft finds a bearing in the standard 5, and has, as illustrated by Figure 5, keyed thereon a cam wheel 35. The cam wheel has two opposed flat faces designed for engagement by the upright arm 36 of a spring member.

The second angle arm of the spring member is fixed to a block 36' secured between the sides of the standard 5. The frictional contact of the spring 36 with the referred to flat faces of the cam 35 is regulated by an adjustable element 37 which is preferably in the nature of a headed bolt having its outer end in contact with one of the sides of the standard 5, and having screwed thereon a nut 38 that contacts with what may be termed the outer face of the spring 36.

The hollow frame or housing 33 has one of its faces closed by a hinged door or frame 38 secured in closed position on the housing proper by latching means 39. The door 38 provides one of the faces of the housing. The opposed open faces of the housing are covered by transparent plates 40 and 41 respectively. The plates in turn for a distance greater than one-half of the length thereof are covered by non-transparent sheets 42 and 43 respectively. These sheets are arranged at diagonally opposed positions so that the transparent plates 40 and 41 extending therebeyond provide diagonally opposed sight openings on the opposed faces of the housing.

The ends, and if desired, the inner sides of the housing have arranged thereon compressible strips 44 which provide cushion elements for frames 45 that have removably arranged therein cards 46 containing advertising matter. In this connection it might be well to state that the cards in the frame may illustrate views of important places in cities, photographs, or in fact, any picture

which may prove of interest to the spectators so that the device is not necessarily restricted to use as an advertising medium.

The hollow housing 33 has centrally secured upon its inner sides cleats 45. These cleats project longitudinally only a slight distance from the said sides of the housing and are spaced away from the faces thereof. The distance between the faces and the edges of the cleats is slightly in excess of the thickness of the frames 45.

Assume the housing to be in vertical position, as disclosed in Figure 3 of the drawings, it will be noted that the frames 45 fill the lower compartment of the said housing, while the number of frames in the upper compartment is only one less than that in the lower compartment. It will be also observed that one of the end frames in the upper compartment is partly projected through the passage provide between the cleats 45 and the face 41 of the housing, and that this frame rests upon the end frame in the lower compartment. It will be further observed that the outer end frame in the lower compartment is in a position to travel through the passage 47 between the face 40 and the cleats 45.

The operation of the device may be briefly described as follows:

Incident to the intermeshing gears between the shaft 19 and the motor shaft, the first mentioned shaft will be turned at a comparatively slow speed. When the chain 26 is turned to bring one of its fingers 34 against one of the shoulders of the cam wheel 29 the latter will be turned one-half a revolution which, of course, turns the stub shaft 27 to revolve the housing 33. This reverses the relative position of the compartments of the housing and shifts the frames 45, so that the outer card, indicated for distinction by 49 in Figure 3 of the drawings and which was at display position, to move through the passage 47 into the adjacent compartment, and causes the remaining cards in the first mentioned compartment to move or shift so that the card next to the card 49 will assume the position previously occupied by said card 49. In a like manner the card in the upper compartment next to the face 41 of the housing, indicated in Figure 3 by the numeral 50, will slide into what was termed the lower compartment. This operation is continuous as long as the housing is turned, so that all of the cards will be separately brought to display position and held in such position for a length of time equalling the period of travel of the next pin 32 on the chain 26 for contacting engagement with the next shoulder on the cam wheel 29. To compensate for the shock incident to the pin leaving the shoulder on the cam wheel, the spring 26 is employed, the said spring being in the nature of a

shock absorber, and to positively hold the frame-like housing in vertical positions the spring 36, contacting with the straight faces of the cam wheel 35 is utilized.

5 The construction, operation, advantages as well as the simplicity of my improvement will, it is thought, be apparent from the foregoing disclosure, but it is to be understood that I have herein set forth only a 10 satisfactory exemplification thereof and that I hold myself entitled to resort to all such changes and modifications as fall within the scope of what I claim.

Having described the invention, I claim:
15 1. In a device for the purpose set forth, a base having hollow standards thereon, a housing having trunnions journaled in the standards, said housing divided into communicating compartments having cards 20 therein shiftable upon the turning thereof and the diagonally opposed end cards movable from one into the other compartment on such turning, a cam on one of the trunnions having opposed flat faces, spring 25 means engaging therewith when the housing is sustained in upright position, a freely mounted sprocket wheel on the second trunnion, a cam wheel fixed on said trunnion, a motor 30 in the base, shafts driven thereby, means reducing the speed of the outer shaft, a sprocket wheel carried thereby, a sprocket chain trained therearound and around the first mentioned sprocket wheel, said chain having outstanding pins to engage the last 35 mentioned cam to revolve the housing, and means between the second mentioned sprocket wheel and the shaft therefor for absorbing the shock incident to the release 40 of the pin from the cam wheel.

first mentioned sprocket wheel, and said chain having outstanding pins to engage the last mentioned cam to revolve the housing. 35

2. In a device for the purpose set forth, a base having hollow standards thereon, a housing having trunnions journaled in the standards, said housing divided into communicating compartments having cards 40 therein shiftable upon the turning thereof and the diagonally opposed end cards movable from one into the other compartment on such turning, a cam on one of the trunnions having opposed flat faces, spring means engaging therewith when the housing is sustained in upright position, a freely mounted sprocket wheel on the second trunnion, a cam wheel fixed on said trunnion, a motor 45 in the base, shafts driven thereby, means reducing the speed of the outer shaft, a sprocket wheel carried thereby, a sprocket chain trained therearound and around the first mentioned sprocket wheel, said chain having outstanding pins to engage the last 50 mentioned cam to revolve the housing, and means between the second mentioned sprocket wheel and the shaft therefor for absorbing the shock incident to the release 55 of the pin from the cam wheel.

In testimony whereof I affix my signature.

JOHN F. RYAN.
